(57) **CLAIM**

The ornamental design for a fuel tank cover, as shown and described.

DESCRIPTION

FIG. 1 is a perspective view of a fuel tank cover showing the new design, the broken lines, which outline the back portion of a vehicle, for illustrative purposes only and form no part of the claimed design;

FIG. 2 is a second perspective view thereof;

FIG. 3 is a back elevation view thereof;

FIG. 4 is a front elevation view thereof;

FIG. 5 is a top view thereof;

FIG. 6 is a bottom view thereof;

FIG. 7 is a left side elevation view thereof;

FIG. 8 is a right side elevation view thereof; and,

FIG. 9 is a left side elevation view thereof, the broken lines, which outline the left side of a fuel tank, for illustrative purposes only and form no part of the claimed design.
